UNITED STATES PATENT OFFICE.

FRANK C. HOYT, OF CLEVELAND, OHIO.

DESIGN FOR A FACE-PLATE FOR SCALES.

SPECIFICATION forming part of Design No. 27,745, dated October 19, 1897.

Application filed January 21, 1897. Serial No. 620,147. Term of patent 14 years.

To all whom it may concern:

Be it known that I, FRANK C. HOYT, a citizen of the United States, residing at Cleveland, in the county of Cuyahoga and State of Ohio, have invented and produced a new and original Design for Face-Plates for Scales, of which the following is a specification, reference being to the accompanying drawings, forming a part thereof.

The drawings clearly show my design for a face-plate for scales.

Figure 1 is a front elevation of the face-plate; and Fig. 2 is a horizontal section of the same, being taken on the line 2 2 of Fig. 1.

The leading features of my design consist, first, in the two openings through the plate, which openings extend in opposite directions from points near the center of the plate to points near its edge; second, in dividing each of said openings into a plurality of small openings by transverse bars; third, in providing said plate with a segmental opening near one edge.

The claim also enumerates the essential features of my design. 25

Referring to the parts by letters, A represents the plate, and B and C represent the horizontal openings. Said openings are divided into small openings b and c by the transverse bars b' c', which are preferably located on the back side of the plate. 30

D represents the segmental opening near the edge of the plate. The center of the plate is also the center of the curve of the opening.

What I claim is—

The design for a face-plate for a scale, substantially as shown and described.

In testimony whereof I affix my signature in presence of two witnesses.

FRANK C. HOYT.
